UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

MECHANISM FOR OPERATING SLIDING DOORS.

Application filed September 21, 1921. Serial No. 502,124.

To all whom it may concern:

Be it known that I, ELLIS J. G. PHILLIPS, a citizen of the United States, and a resident of Aurora, in the county of Kane and State 5 of Illinois, have invented certain new and useful Improvements in Mechanism for Operating Sliding Doors, of which the following is a specification, reference being had to the accompanying drawing.

10 This invention relates to improved means for operating sliding doors and particularly doors employed for guarding the openings that admit passengers and goods to and from elevators at the various floors of a building.

15 My invention is especially designed for use in connection with mechanism of the type shown and described in Letters Patent No. 1,203,413, dated October 31, 1916, granted upon the application of one Albert J. Rosen- 20 treter, and it has for its object to provide improved means for permitting ready disconnection from or connection to a sliding door of the system of levers that are employed in connection with such door. I ac- 25 complish this object by the novel construction and arrangement of parts shown in the drawing and hereinafter particularly described. That which I believe to be new will be set forth in the claims.

30 In the drawings,—

Fig. 1 is a front elevation showing a door closing mechanism operatively connected to a sliding door, such mechanism embodying my improvements;

35 Fig. 2 is a similar view on an enlarged scale, portions of the operating mechanism being broken away;

Fig. 3 is a section taken on the line 3—3 of Fig. 2; and

40 Fig. 4 is a detail, being a perspective view of the bolt that detachably secures the lever mechanism in operative relation with the door.

Referring to the several figures of the 45 drawing, 5 indicates a sliding door and 6 indicates a fixed panel or non-sliding door, which member 6 as explained in said Patent No. 1,203,413, will ordinarily be hinged in place so that, when desired, it may be turned

50 out of the way in order to provide a full width opening to the elevator as is necessary when furniture or large pieces of freight are to be placed in or removed from the elevator. Such opening of the doorway for such pur-

55 poses necessitates also the swinging to one

side of the sliding door, and the means by which the sliding door is hung are constructed to permit such swinging, but as such means are well known in the art, I have not herein shown them. As explained in said Letters Patent, there may be one or more sliding doors employed, and when there is more than one door the operating mechanism is to be attached to the outermost one, but inasmuch as it is immaterial, so far as 60 my invention is concerned, whether one sliding door or a plurality of such doors be employed, I have illustrated it in connection with a single sliding door. This sliding door, 5, in its opening and closing movements 65 70 slides close to one face of the non-sliding member 6, as is well understood.

Referring to the operating mechanism, 7 and 8 indicates respectively two levers pivoted together at their inner end portions by 75 a pivot 9, and together forming a toggle-lever. The outer end of the lever 7 is pivoted at 10 to a bracket 11 affixed to a suitable support such as a portion of the doorway frame. As explained in said Letters Patent, 80 the lever 7 is best formed of two spaced-apart members between end portions of which the single lever 8 projects. The inner end of the lever 8 has secured to it a disc 12 to which one end of a flexible connection 85 13 is secured, the other end of which connection is made fast to a follower (not shown) that is located in a cylinder 14 that carries a coiled spring that is compressed when the toggle is broken in the act of opening the door. 15 indicates an ordinary check, the movable stem of which is connected with the lever 7, such check acting to cushion the door so that it will close quietly as is well understood. Near the inner ends 90 of the two members that constitute the lever 7 is a pin 16 that is adapted to enter a notch in the lever 8 when the toggle is in the position shown in Fig. 1. The parts so far briefly referred to are well known, and are fully 100 illustrated and described in said Patent No. 1,203,413, and hence a more detailed description of them is not deemed necessary.

In said former construction the lever 8 was, at its outer end, pivotally connected 105 with a plate on the sliding door, but in my improved construction I interpose between the lever 8 and the pivot on the sliding door a comparatively short arm, which arm has a pivotal connection with the sliding door. 110

The arm referred to is indicated by 17 and at one end is secured upon a pivot 18 that projects from the outer face of a plate 19 that is made fast to the sliding door, preferably by being screwed to the inner stile thereof. The free end of the arm 17 is provided with a socket 20 of such size and shape as to receive and hold therein an end portion of the lever 8, such socket being preferably of considerable depth as clearly illustrated by dotted lines in Fig. 2.

To the lever 8 is fixedly secured a stud 21 that projects from the outer face of such lever, said stud being provided with an enlarged head 22. Surrounding the stud is a short sleeve or hollow bolt 23 and located therein, as clearly shown in Fig. 3, is a coiled spring 24 which at its outer end bears against the enlarged head 22 and at its inner end against an annular inturned flange at the inner end of the sleeve-like bolt 23. At opposite sides of the bolt at its inner end are lugs 25 which are preferably cast with the member 23. The outer wall of the socket 20 in the arm 17 is provided with an open-ended slot 26 of a size to receive therein the bolt 23, and in the side walls of this slot are recesses 27 into which the lugs 25 are adapted to rest, and when such lugs are in their respective recesses it will be evident that the lever 8 will be held against end-wise movement that would detach it from the arm 17.

28 indicates an operating handle pivotally mounted on the pivot 18 which handle at its inner end has rigidly fastened thereto or formed therewith a downwardly-extending arm 29 from the outer face of which extends a projection 30 that is normally in engagement with the lower edge of the arm 17. The free end of the lever 28 will preferably have connected therewith a hand-hold 31 of any ordinary shape.

In operation, by pressing down upon the handle 28 sufficient pressure will be brought against the lower side of the arm 17, through the projection 30, to cause a breaking of the toggle at its joint 9, and thereafter the sliding door 5 will be moved back out of closing position—the mechanism in both the opening and closing operations of the door acting in the manner fully described in said Letters Patent. Whenever it is desired to so disconnect the operating mechanism from a sliding door as to permit of a full opening of the doorway as before referred to, such disconnection can be instantly made by drawing out the sleeve-like bolt 23 against the action of the coiled spring 24 therein, such drawing out continuing until the lugs are clear of the recesses 27, after which such bolt can be given a slight turn to keep them from being forced by the spring back into the recesses. At 32 is shown another recess, similar to the recesses 27, into which one of the lugs can

drop when the bolt has been given a quarter turn. After the withdrawal of the lugs from their holding or retaining position in the recesses 27, it is evident that upon the toggle being broken on its joint 9, the lever 8 can be instantly withdrawn from its socket in the arm.

By providing this comparatively short arm 17 between the pivot on the sliding door and the end portion of the adjacent lever, and providing also for a detachable connection between said arm and lever, such as illustrated and described, I am able to quickly connect or disconnect said arm and lever, and yet when the parts are in operative position said arm and lever will be rigid, one with the other, and, therefore, the action of the toggle lever as a whole will be as perfect as if the lever 8 were itself directly connected with the pivot on the door as in the former construction.

What I claim as my invention and desire to secure by Letters Patent, is—

1. Sliding door operating mechanism comprising in combination, an arm adapted to be pivotally connected at one end with a door, and a pair of toggle-levers pivotally connected together at their inner ends, one of which levers is adapted to be pivotally connected at its outer end with a fixed support, the outer end of the other lever being interlocked with and forming a rigid prolongation of said arm.

2. Sliding door operating mechanism comprising in combination, an arm adapted to be pivotally connected at one end with a door, a pair of toggle-levers pivotally connected together, one of which levers is adapted to be pivotally connected with a fixed support, and means for detachably connecting an end portion of the other lever with said arm and serving also to hold said last-named lever rigid with said arm.

3. Sliding door operating mechanism comprising in combination, an arm adapted to be pivotally connected at one end with a door, a pair of toggle-levers pivotally connected together, one of which levers is adapted to be pivotally connected with a fixed support, means for detachably connecting an end portion of the other lever with said arm and serving also to hold said last-named lever rigid with said arm, and a pivoted device adapted when swung in one direction to break the toggle.

4. Sliding door operating mechanism comprising in combination, an arm adapted to be pivotally connected at one end with a door and having a socket in its other end, and a pair of toggle-levers pivotally connected together, one of which levers is adapted to be pivotally connected with a fixed support and the other of which has an end portion detachably held in said socket.

5. Sliding door operating mechanism com-

prising in combination, an arm adapted to be pivotally connected at one end with a door and having a socket in its other end, one wall of the socket having an open-ended slot therein, a pair of toggle-levers pivotally connected together, one of which levers is adapted to be pivotally connected with a fixed support and the other of which has an end portion inserted in said socket, and 10 a bolt on said last-named end portion, which bolt fits within said slot.

6. Sliding door operating mechanism comprising in combination, an arm adapted to be pivotally connected at one end with a door and having a socket in its other end, one wall of the socket having an open-ended slot therein, a pair of toggle-levers pivotally connected together, one of which levers is adapted to be pivotally connected with a 15 fixed support and the other of which has an end portion inserted in said socket, and a bolt on said last-named end portion, which bolt fits within said slot, said bolt having an interlocking engagement with a wall of the 20 slot.

7. Sliding door operating mechanism comprising in combination, an arm adapted to be pivotally connected at one end with a door and having a socket in its other end, 25 one wall of which socket has an open-ended slot therein, a pair of toggle-levers pivotally connected together, one of which levers is

adapted to be pivotally connected with a fixed support and the other of which has an end portion lying within said socket, a longitudinally-movable bolt on said last-named end portion, said bolt lying within said slot and having a lug thereon for entering a recess in said slotted wall to lock said last-named toggle-lever against withdrawal from 35 the socket, and a spring tending to normally hold said bolt in locking position.

8. Sliding door operating mechanism comprising in combination, an arm adapted to be pivotally connected at one end with a door and having a socket in its other end, one wall of which socket has an open-ended slot therein, a pair of toggle-levers pivotally connected together, one of which levers is adapted to be pivotally connected with a 40 fixed support and the other of which has an end portion lying within said socket, a stud secured to said last-named end portion, a hollow bolt surrounding said stud and movable thereon and fitting within said slot, 45 said bolt having a lug thereon for engagement with a recess in said slotted wall to effect a locking of said last-named toggle-lever to said socketed arm, and a coiled spring interposed between said stud and 50 bolt for normally holding the bolt in its 55 said locking position.

ELLIS J. G. PHILLIPS.
